PAVEMENT JOINT CLEANING

Filed April 25, 1938

UNITED STATES PATENT OFFICE

2,185,052

PAVEMENT JOINT CLEANING

Samuel W. Dougherty, Greencastle, Pa.

Application April 25, 1938; Serial No. 204,200

6 Claims. (Cl. 37—169)

This invention relates to hand operated tools especially adapted for removing foreign matter from road surfaces and the joints of concrete roads and the like and has for the primary object the provision of a tool of the above stated character whereby a person may with ease and quickness condition a road joint and road surface for recementing or calking wherein it is essential to have the joint or road surface free of dirt and other foreign matter before the cement or calking material is applied.

Another object of the invention is the provision of a portable tool holder requiring only minimum effort on the part of the operator for its movement over a road surface and which is equipped with cutting and scraping tools easily brought into place for use and held against loss when not in use.

With these and other objects in view, this invention consists in certain novel features of construction, combination and arrangement of parts to be hereinafter more fully described and claimed.

For a complete understanding of my invention, reference is to be had to the following description and accompanying drawing, in which

Figure 1 is a fragmentary side elevation illustrating a tool constructed in accordance with the invention.

Figure 2 is a fragmentary top plan view showing the device adjusted for scraping a road surface or the like.

Figure 3 is a sectional view taken on line 3—3 of Figure 1.

Figure 4 is a fragmentary vertical sectional view showing the tool adjusted for cleaning foreign matter from a cement road joint.

Figure 5 is a view similar to Figure 4 showing a modification of the present invention.

Figure 6 is a fragmentary top plan view showing the modification.

Referring in detail to the drawing, the numeral 1 indicates a body of the tool holder and which is of elongated formation and has detachably secured on one end a handle 2.

Formed on the body 1 adjacent the other end thereof are pairs of shoulders or lugs 3 and cooperating with said lugs in gripping a shank 4 of a tool is a clamp 5 consisting of a member 6 to fit between the pairs of lugs and overlie the shank of the tool. Integral with the member 6 are oppositely arranged apertured ears 7 through which bolts or like fasteners 8 extend. The fasteners 8 are secured in the body 1. The pairs 55 of lugs 3 and the member 6 cooperate in remov-

ably securing the tool on the holder or body 1 and against relative movement thereto during a cleaning operation. The tools may be of various kinds and shape some of which are to operate in a road joint for the purpose of scraping or cutting therefrom dirt and other foreign matter accumulated in the joint so as to prepare the joint to be recemented or calked. One of the tools is in the form of a blade 9 and having a shank 10 secured thereto. The blade 9 is of a selected width having scraping or cutting edge presented for movement over a surface of a road to scrape therefrom foreign matter, as shown in Figure 1. The tools when not in use are removably mounted on the body 1 by a clamp 11. A substantially U-shaped member 12 is pivotally mounted on the body 1 adjacent the securing lugs 3 and has integral therewith spaced legs 13 on which are journaled rollers 14 to ride the surface of a road during either the cutting or scraping operation.

Formed on the U-shaped member 12 and extending upwardly therefrom is an arm 15 to which is pivoted a flexible rod 16 one end of which is disposed angularly thereto to enter any one of a series of sockets 17 formed in the body. Said end of the rod may be readily moved from one socket to another for adjusting the cutting action of the blade necessary for different joints in a roadway. The rod adjacent the latter-named end is coiled to give desired resiliency to said rod.

Secured to the rod 16 is a coil spring 18 and the latter is secured on the body 1 and acts to urge the rod 16 in the direction of the body to retain one of its ends in engagement with a socket.

The legs 13 move relative to the body 1 in accordance with the amount of manual pressure placed on the body. The substantial normal position of the legs 13 is as shown in Figure 1 so as to position the rollers 14 in a plane slightly below the tool carried by the body so that the rollers may move over a surface with the tool in engagement with the surface. However, when cleaning a crack or joint in the roadway additional manual force is applied on the member 1 causing the legs to swing past and above the tool as shown in Figure 4, still contacting the surface of the roadway with the tool extending fully into the crack or joint so that as the device is moved along the crack or joint foreign matter will be cut, scraped or otherwise removed from the crack or joint.

Referring to my modified form of invention a tool holder 19 is provided which consists of a

member 20 having a shank 21 extending upwardly from one end. The shank 21 is secured on the body 1 by the clamp 5 and lugs 3. When the body 1 is disposed in an operating position 5 with the rollers in engagement with the surface of the road the member 20 is disposed substantially horizontally to the surface of the roadway and has pivoted to its forward end an arm 22. A coil spring 23 is connected to the member 20 10 and to the arm 22 urging the latter downwardly toward the member 21. The member 21 is of a bifurcated construction through which a tool 24 may extend. The tool is carried by the arm 22. The cutting end of the tool when so mounted on the body 1 is disposed in a plane below the rollers 15 for operation in a crack or joint of a roadway and is capable of yielding upwardly if engaged with an obstruction due to the arrangement of the pivoted arm 22 and the spring 23.

20 What is claimed is:

1. A device for preparing road joints and road surfaces comprising a body, a handle for said body, means for detachably mounting on said body different types of tools, means on said body 25 for supporting said tools when not in use, a substantially U-shaped member pivoted on said body, legs integral with said U-shaped member and extending forwardly and downwardly on opposite sides of the body and the tool carried 30 thereby, rollers journaled on said legs to ride the surface of the road, an arm integral with said U-shaped member and extending upwardly and forwardly with respect to the body, said body having a series of openings, a resilient rod pivoted 35 to said arm and adapted to have an end thereof insertible in any one of the sockets.
2. A device for preparing road joints and road surfaces comprising a body, a handle for said body, means for detachably mounting on said 40 body different types of tools, means on said body for supporting said tools when not in use, a substantially U-shaped member pivoted on said body, legs integral with said U-shaped member and extending forwardly and downwardly on opposite sides of the body and the tool carried 45 thereby, rollers journaled on said legs to ride the surface of the road, an arm integral with said U-shaped member and extending upwardly and forwardly with respect to the body, said body having a series of openings, a resilient rod pivoted 50 to said arm and adapted to have an end

thereof insertible in any one of the sockets, and a coil spring connected to said rod and to said body and acting to urge the rod toward the body.

3. A device for preparing road joints and road surfaces comprising an elongated body, clamping means carried by said body, rollers yieldably and pivotally mounted on said body to engage with a surface, a shank secured on said body by the clamp and extending forwardly thereof in a plane parallel with the said surface supporting 10 the rollers, an arm pivoted to the shank, a tool carried by the said arm, and resilient means co-acting with the tool and the said shank to yieldably support the tool in a working position and a tool carried by said shank.

4. A device for preparing road surfaces and joints comprising an elongated body, a handle connected to one end of said body, clamping means carried by said body adjacent the other end thereof, rollers yieldably and pivotally 20 mounted on said body to engage with a surface, a shank secured on said body by the clamp and extending forwardly thereof, a member integral with said shank and extending forwardly thereof and in a plane substantially paralleling a plane 25 of the surface supporting said rollers, an arm pivoted on said member and extending upwardly and rearwardly in the direction of the body, a tool carried by said arm and having its work end disposed below said member, and a spring connecting the arm and member to yieldably support the tool in a working position.

5. A device comprising an elongated body, having a plurality of openings, a bracket pivoted to the body, rollers journaled to the said bracket, 35 and a resilient rod having one end pivotally attached to the bracket and adapted to have the other end thereof inserted in any of the said openings.

6. A device comprising an elongated body, 40 having a plurality of openings, a bracket pivoted to the body, rollers journaled to the said bracket, a resilient rod having one end pivotally attached to the bracket and adapted to have the other end thereof inserted in any of the said openings, and 45 a tool detachably secured to the said body having the positioning of the working end thereof controlled by selectively positioning the end of the resilient rod in various of the said openings.

50 SAMUEL W. DAUGHERTY.
